UNITED STATES PATENT OFFICE.

GUY C. COFFEY, OF VIRGINIA, MINNESOTA, ASSIGNOR OF ONE-HALF TO MARK ELLIOTT, JR., OF VIRGINIA, MINNESOTA.

DESIGN FOR A BULLETIN BOARD.

Application filed May 11, 1925. Serial No. 13,395. Term of patent 14 years.

To all whom it may concern:

Be it known that I, GUY C. COFFEY, a citizen of the United States, residing at Virginia, in the county of St. Louis and State of Minnesota, have invented a new, original, and ornamental Design for Bulletin Boards, reference being had to the accompanying drawing forming part thereof.

The figure is a perspective view of a bulletin board, showing my new design.

I claim:

The ornamental design for a bulletin board, as shown.

GUY C. COFFEY.
